UNITED STATES PATENT OFFICE.

HENNING KLOUMAN, OF MICHIGAN CITY, INDIANA, ASSIGNOR TO CHROBALTIC TOOL COMPANY, A CORPORATION OF ILLINOIS.

METHOD OF MAKING METAL CASTINGS.

Application filed September 18, 1925. Serial No. 57,143.

The invention relates to the method of making metal castings within which are embedded, during the casting operation, previously formed parts, such as sheet metal panels, and, which, in the finished article, are offset inwardly from the surface of the casting.

The invention consists of the method hereinafter described, and in the accompanying drawing illustrating its employment there is shown in

Fig. 1, a view in perspective of the carburing box, some portions being broken away.

Fig. 2, a detail vertical section of the mold, cores and the box wall; and

Fig. 3, a view in perspective of an adjustable section of the core and the metal insert carried thereby.

The article, to the manufacture of which the improved method is applicable, is shown as a box comprising a cast wall 10, having a sheet metal panel 11 which is cast into the wall. The drag element 12 of the mold is filled with sand, as represented at 13, within which is formed, by suitable patterns, an impression of the outer surface of the box which is to be molded. The sheet metal panel 11 being set in a short distance from the outer face of the box wall, the sand impression necessarily comprises a boss 14 of the contour of the opening in the casting to be formed, against the face of which boss the panel insert 11 must be closely fitted to prevent the metal from flowing over its surface.

The mold is completed by the insertion into the cavity in the sand 13 of a core 15, having the contour to be given the inner surface of the casting to be formed. An opening is left in the side wall of the core 15 of a size and shape corresponding to the sheet metal panel which is to be embedded in the casting. Within this opening there is fitted a movable core block 16, to the outer face of which the sheet metal panel 11 is secured, as by means of pins 17. The panel is of greater area than the face of the core block to provide marginal sections which will be embedded within the casting. Be-

fore insertion of the core 15 into the cavity 50 of the mold, the block 16 is entered into its aperture, the marginal portions of the insert 11 being in contact with the outer face of the core 15.

The completed core is now placed within 55 the mold and the insert 11, being set in beyond the position it is to occupy, will pass the boss 14 without contact therewith and, consequently, without injury thereto. The core 15 being properly positioned, the block 60 16 is forced outwardly to bring the insert 11 into contact with the face of the boss 14, thus moving its marginal portions away from the outer surface of the core 15, its marginal portions overlapping the boss. 65

The metal being poured in the usual manner, will flow about and envelop the marginal portions of the insert and complete the structure as illustrated in the drawings. The box comprises a sheet metal panel in 70 its bottom wall, as shown at 18, but this insert is readily placed in the mold in the usual manner and without involving any difficulty in avoiding the mutilation of the sand mold. 75

I claim:

1. The method of forming a mold for the casting of chambered bodies having an insert embedded within the wall thereof during the casting operation, and set in from 80 the faces of such wall, consisting in the formation of a sand mold conforming to the exterior face of the body, a core conforming to the interior face thereof but having an aperture conforming in shape and location to the insert, forming a core block conforming to such aperture, attaching the insert to the outer face of the block, entering the block into the aperture to bring the margins of the insert in contact with the 85 first mentioned core, fitting the assembled core elements into the sand mold, and then forcing outwardly the block to cause the insert to make contact with the sand. 90

2. The method of casting chambered bodies comprising previously formed inserts embedded in the cast metal and set in from the face of the body, consisting in forming 95

a sand mold of the contour of the exterior of the body, providing a core conforming to the interior contour of the cast portion of the body and having an aperture corresponding to the location and shape of the insert, inserting into such aperture a core block to which the insert is affixed, placing the assembled

cores within the sand mold, forcing outwardly the core block to bring the insert into contact with the sand, and pouring the molten metal into the completed mold.

5 In testimony whereof I affix my signature.

HENNING KLOUMAN.
